(57) **CLAIM**

I claim the ornamental design for a boat, as shown and described.

DESCRIPTION

FIG. 1 is a top side perspective view showing my new design;
FIG. 2 is a side view thereof;
FIG. 3 is a top view thereof;
FIG. 4 is a bottom view thereof;
FIG. 5 is a front view thereof; and,
FIG. 6 is a back view thereof.
The broken lines form no part of the claimed design.
